COVER FOR LOOSE LEAF BOOKS

John J. Rickert, Elmore, N. J., assignor to
Boorum & Pease Company, Brooklyn, N. Y.,
a corporation of New York

Application June 28, 1934, Serial No. 732,933

7 Claims. (Cl. 129—24)

The invention relates to reinforcements for somewhat flexible covers for loose leaf books and particularly to such books in which means securing the hinge between the back and the side covers of the book pass through the material of the side covers.

A purpose of the invention is to provide a reinforcement for the cover at the hinge. A further purpose is to provide a protector for the cover so that the rings of the book will not readily mark the cover.

The invention is illustrated in the accompanying drawings, of which:

Figure 1 is a perspective view of the back and part of the side covers of an open loose leaf book, showing the invention, portions of the book being broken away;

Figure 2 is a portion of a blank for the cover of a loose leaf book showing the novel reinforcing strips in place before the back metal has been added to the book;

Figure 3 is a cross section on the line 3—3 of Figure 2, somewhat enlarged;

Figure 4 is a section similar to Figure 3, showing a modification;

Figure 5 is a cross section through a closed loose leaf book embodying the invention, taken on a line similar to line 5—5 of Figure 1;

Figures 6, 7 and 8 are figures similar to Figure 1, but showing modifications.

As illustrated in the drawings, side covers 10 of the loose leaf book may be made of any suitable somewhat flexible material. The side covers may be partially joined together at the ends of the book, as shown at 11 in Figures 1 and 2, or they may be wholly separated from each other, as shown in Figure 6. Each side cover 10 is hinged to the back 12 by any suitable hinge 13, which is secured to the back and the side cover 40 by means 14 which passes through the back and the side cover. The back 12 is provided with the usual back-metal 15 carrying the usual rings 16.

A reinforcing strip 17 is secured to the side cover 10 along the hinge 13. It may be secured 45 by cementing or by any other suitable means. Strip 17 may be an integral part of side cover 10 folded back upon itself as illustrated for example in Figures 3 and 5, or it may be a separate strip as shown at 170 in Figures 4 and 6.

The reinforcing strip may extend from edge to edge of the cover, as shown at 170 in Figure 6, or it may extend only a portion of that distance, as shown in Figures 1, 2 and 8, or at 171 in Figure 7. This Figure 7 shows each side cover 10 provided with a series of short reinforcing strips 171,

instead of with one continuous reinforcing strip, as illustrated in some of the other figures.

It will be seen that means 14 which secure the hinge 13 to the side cover 10 pass through both the side cover 10 and the reinforcing strip 17. Thus the strip 17 provides a reinforcement of the side cover 10 against the strain exerted by the weight of the side cover and by the opening and closing of the hinge. At the same time the reinforcing strip provides a protection to the cover 10 against marking by the ring 16 at the point 18 where the arc of the ring would otherwise bear against the cover 10, as can be seen particularly in Figure 5.

The hinge may be of any suitable sort. In Figures 1, 5, 6 and 7 a stitched hinge is shown. In these figures stitches 14 comprise the means which secures the hinge 13 to the side cover. In Figure 8 a metal hinge 130 is shown secured to the side cover 10 by any suitable means, such as 20 rivets 140, which pass through a reinforcing strip 17 and side cover 10. Any other suitable hinge and any other suitable means of attaching the hinge to the side cover may be used.

The described construction is particularly useful in making practical for book covers cheaper material than would otherwise be desirable. It can be used with particular advantage with imitation leather or thin leather or other like materials.

I claim:

1. In a loose leaf book having rings, a cover comprising a back, a side cover and a hinge, in combination with a reinforcing strip lying between said side cover and its point of contact with a ring and secured to said side cover, and means securing the hinge to the side cover passing through said reinforcing strip.

2. In a loose leaf book having rings, a cover comprising a back, a side cover and a hinge, means securing the hinge to the side cover in combination with a reinforcing strip lying between said side cover and its point of contact with a ring and secured to said side cover by the means which secures the hinge to the side cover.

3. In a loose leaf book having rings, a cover comprising a back, a single ply side cover and a hinge, in combination with a reinforcing strip lying between said side cover and its point of contact with a ring and secured to said side cover, and means securing the hinge to the side cover passing through said reinforcing strip.

4. In a loose leaf book having rings, a cover comprising a back, a flexible side cover and a hinge, in combination with a reinforcing strip ly-

- ing between said side cover and its point of contact with a ring and secured to said side cover, and means securing the hinge to the side cover passing through said reinforcing strip.
5. In a loose leaf book having rings, a cover comprising a back, a single ply side cover and a hinge, means securing the hinge to the side cover in combination with a reinforcing strip lying between said side cover and its point of contact with
- 10 a ring and secured to said side cover by the means which secures the hinge to the side cover.
6. In a loose leaf book having rings, a cover comprising a back, a flexible side cover and a

hinge, means securing the hinge to the side cover in combination with a reinforcing strip lying between said side cover and its point of contact with a ring and secured to said side cover by the means which secures the hinge to the side cover. 5

7. In a loose leaf book having rings, a cover comprising a back, a side cover and a hinge, in combination with a reinforcing strip integral with and lying between said side cover and its point of contact with a ring, and means securing the hinge to the side cover passing through said reinforcing strip. 10

JOHN J. RICKERT.
